SPOUT SUPPORT FOR RAILWAY WATER COLUMNS

John T. McGarry, Cincinnati, Ohio

Application October 23, 1936, Serial No. 107,168

7 Claims. (Cl. 137—21)

My invention relates to spout supports for railway water columns and has for its object to provide in a water column designed to deliver water to the tenders of locomotives, a spout and a means of supporting the same which shall be simple in construction and particularly satisfactory and efficient in operation.

It is a particular object of my invention to provide a spout which at its inner or water receiving end shall have a cross section elongated in a vertical direction and to support said spout, or the butt end thereof, on a butt-roller mounted within the spout and having a contact with the top of the goose-neck discharge nozzle of the water column which shall cover a considerable part of the transverse circumference of the goose-neck amounting to $\frac{1}{8}$ or more thereof, and which shall have its axial support in the upper part of the butt end of the spout.

It is a further object of my invention to provide restraining chains each having pivotal connection at one end with the standpipe and at the other end with the butt end of the spout substantially in line with the axis of the butt-roller, and to form in conjunction with said restraining chains a spring shock absorber acting to yield when the body of water delivered from the goose-neck nozzle first strikes the spout, absorbing the shock or blow transmitted to said chains without danger of breakage.

Full objects and advantages of my invention will appear in connection with the detailed description thereof and its novel features will be particularly pointed out in claims.

In the drawings illustrating an application of my invention in one form, Fig. 1 is a side elevation view of a portion of a railway water column or standpipe showing the position and form, and the manner of mounting and supporting the spout. Fig. 2 is a cross-section taken on line 2—2 of Fig. 1 on an enlarged scale. Fig. 3 is a fragmental side elevation sectional view of the butt end of the spout taken along the spout across the center of the butt roller. Fig. 4 is a detailed sectional view taken on line 4—4 of Fig. 2.

As illustrated, the spout 10 has secured to the margin of its rear end 11 a ring casting 12 to which the metal of the spout 11 is secured by rivets, welding or any desired known method. In the upper portion of the rear or butt-end portion 11 of the spout 10 is secured in any desired manner such as by bolts 13, a U-piece 14 having arms 15 and 16, within which is mounted an axle pin 17.

Mounted to rotate upon this axle pin 17 is a spool or butt-roller 18, which has an external

contour 19 roughly spool-shaped with end bearing portions 18a and 18b adapted to contact with inner end parts of a transverse arc indicated at 20 of the top surface of the goose-neck or nozzle 21 of the standpipe proper, and this arc so contacted by surface 19 of butt-roller 18 will comprise a substantial part of the circumference of the upper surface of the goose-neck preferably equalling or in excess of $\frac{1}{8}$ of said circumference.

Having reference to Fig. 2 and to the transversely elongated cross-sectional form of the spout 10, and of its butt-end 11, and noting the position of the butt-roller 18 close to the top of this elongated portion and the engagement of the surfaces 18a and 18b with the surface of the goose-neck far above the center of any transverse section of the butt-end 11 of spout 10, it will be apparent that gravity will tend to hold the spout in proper position with its longer dimension vertical and with the surface 19 of the butt-roller 18 riding upon the upper surface of the top of the goose-neck, as indicated at 20 in Fig. 2.

The front end of the spout is supported in a well-known manner by means of a cord 22 connected to a point 23 on the spout and toward its front end, said cord passing over guide rollers 24 and 25 to a ring weight 26 surrounding the standpipe 27 of the water column, the roller 24 being supported from a beam 28 rigidly secured to the upper portion 29 of the standpipe 27.

In delivering water to tenders of engines, as will be apparent from inspection of the drawing Fig. 1, there is a wide range of adaptability of the spout 10 for tenders of greatly varying heights.

Means are provided which will have the effect of restraining the spout at its butt end in its forward movement along the gooseneck 21 when the outer limit of said movement has been reached, and which at the same time will cooperate with the axle shaft 17 and butt-roller 18 to aid in maintaining the spout in correct position along its transverse vertical center. This means comprises chains 30 and 31 connected to pivot pieces 32 and 33, which in turn are pivotally connected to ring casting 12 and butt end 11 of spout 10 by means of pivot bolts 34 and 35. This point of pivotal connection is substantially in line with the axis of the axle shaft 17 for a purpose hereinafter recited. The chains 30 and 31 are connected through U-links 36, 37 and 38, 39 to plate connectors 40 and 41, which in in turn are connected to the standpipe back of the roller 25, as clearly shown in Fig. 1.

In the dotted line position of Fig. 1, very low

tenders will be served, and when the spout is in the position shown on dotted lines, or in positions approaching that dotted line position, the opening of the valve controlling the flow of water and the initial stream discharge from the goose-neck nozzle 21 striking against the upper inside walls of the spout 10 will impinge with such force and shock upon said walls that in some instances the chains 30 and 31 might break, 10 permitting the spout to be torn from its mounting and fastening, and damaging or wrecking the spout and possibly injuring operators.

To secure against this danger I have provided U-link construction 36 and 38 for one chain, 15 and the similar construction 37 and 39 for the other chain. In both instances a strong compression spring 42 takes between upper hooks 43 on lower links 38 or 39, and lower hooks 44 on the upper U-links 36 or 37, so that the spring 20 42 acts as a shock absorber to take up or absorb the force of the blow resulting from the initial discharge of the stream of water against the inner walls of spout 10. This absorption of initial shock effectively prevents breaking of the 25 restraining chains 30 and 31, and wrecking of the spout.

The advantages of my invention will be apparent from the foregoing description. There is a very great advantage in the use of a spout 30 having an elongated cross-section toward the butt end or rear end as indicated in Fig. 2, whereby a large amount of space is available for the discharge of the stream of water from the goose-neck nozzle. Since this discharge is usually at 35 high speed under a very large head, there is a tendency in many positions of the spout, where this amount of space is not available, for the water to back up, regurgitate and splash out of the rear end of the spout resulting in waste of water and in very serious trouble with ice in 40 the winter time. The butt-roller mounting of the rear end of the spout has many marked advantages over any other form of supporting the rear end of the spout. With a spout substantially round in cross-section, or with restraining 45 means toward or below the center of the transverse section of the spout, the use of a butt-roller has not proven entirely satisfactory, because of a tendency for the spout to twist as it is carried down the goose-neck in adjusting to tenders of different heights and of different distances 50 from the standpipe. This twisting tendency is effectively obviated by the use of the wide butt-roller inside the rear end of the spout and close 55 to its top, with the spout having an elongated transverse cross-section as indicated in Fig. 2, and the connection of the restraining means, such as chains 30 and 31, also at the top of the butt end of such a spout and substantially in 60 the horizontal axis of the butt-roller 18. This mounting permits the spout to be drawn out and pushed in without tendency for it to twist or roll over and with the wide butt-roller 18 rolling 65 along the upper surface of goose-neck 21. Furthermore, with this arrangement when the spout reaches the end of its travel with the chains 30 and 31 fully extended, the shock of the initial stream of water upon the upper surface of the spout is absorbed in the spring connection between U-links 36, 38 or 37, 39, thus not only 70 maintaining the spout and its elongated cross-section and butt-roller rear end support in proper position with the butt-roller riding the top of the goose-neck, but preventing the blow of the initial 75

impact of the water from breaking the chains and wrecking the spout.

I claim:

1. A water column comprising a spout of elongated cross-section at its rear-end, said spout rear-end enveloping the goose-neck nozzle of the water column, and said nozzle of circular cross-section, a spool-shaped roller rotatably mounted in the upper part of the rear-end of the spout and shaped to engage the ends of a transverse arc across the major part of the top of said spout, the support of said spool in relation to the elongated cross-section of the rear-end of the spout being such that gravity will maintain the spout in proper vertical relation to the goose-neck nozzle as the spout is drawn out along the same, and a pair of chains having pivotal connection with the rear-end of the spout substantially in line with the axis of said roller. 10 15

2. A water column comprising a spout of elongated cross-section at its rear-end, said spout rear-end enveloping the goose-neck nozzle of the water column and having a supporting band secured to said rear-end, and said nozzle of circular cross-section, a U-member secured to the upper part of said spout and band within the spout and having parallel arms, an axle shaft mounted between said arms, a spool-shaped roller rotatably mounted on said axle-pin and shaped to engage the ends of a transverse arc across the major part of the top of said spout, the support of said spool in relation to the elongated cross-section of the rear-end of the spout being such that gravity will maintain the spout in proper vertical relation to the goose-neck nozzle as the spout is drawn out along the same. 20 25 30 35

3. A water column comprising a spout of elongated cross-section at its rear-end, said spout rear-end enveloping the gooseneck nozzle of the water column and having a supporting band secured to said rear-end, and said nozzle of circular cross-section, a U-member secured to the upper part of said spout and band within the spout and having parallel arms, an axle shaft mounted between said arms, a spool-shaped roller rotatably mounted on said axle-pin and shaped to engage the ends of a transverse arc across the major part of the top of said spout, the support of said spool in relation to the elongated cross-section of the rear-end of the spout being such that gravity will maintain the spout in proper vertical relation to the gooseneck nozzle as the spout is drawn out along the same, and a pair of chains having pivotal connection with said supporting band substantially in line with said axle shaft. 40 45 50 55

4. A water column comprising a spout of elongated cross-section at its rear-end, said spout rear-end enveloping the gooseneck nozzle of the water column and having a supporting band secured to said rear-end, and said nozzle of circular cross-section, a U-member secured to the upper part of said spout and band within the spout and having parallel arms, an axle shaft mounted between said arms, a spool-shaped roller rotatably mounted on said axle-pin and shaped to engage the ends of a transverse arc across the major part of the top of said spout, the support of said spool in relation to the elongated cross-section of the rear-end of the spout being such that gravity will maintain the spout in proper vertical relation to the gooseneck nozzle as the spout is drawn out along the same, and a pair of chains each including a shock absorber for limiting movement of spout along the gooseneck nozzle, 60 65 70 75 80 85 90 95 98 99

said chains having pivotal connection with said supporting band substantially in line with said axle-shaft.

5. A water column comprising a standpipe and gooseneck nozzle supported on the upper part thereof of circular cross-section, a spout having an enlarged intermediate portion and a contracted inner end surrounding said gooseneck and of a cross-section considerably longer in one direction than in the other direction, and a spool-shaped roller secured within the inner end of said spout at its top and extending transversely parallel with the shorter diameter of said spout-end, said spool having separated bearing surfaces 10 forming a spout support engaging the upper surface of said gooseneck at points normally equidistant from a vertical plane passing through the center of the gooseneck, said spout support having such relation to the elongated cross-section 15 of the inner end of the spout and the circular cross-section of the gooseneck as will cause gravity to maintain the spout in proper vertical relation to the gooseneck nozzle as the spout is moved along the same.
- 20 6. A water column comprising a standpipe and gooseneck nozzle supported on the upper part thereof of circular cross-section, a spout having an enlarged intermediate portion and a contracted inner end surrounding said gooseneck and of a cross-section considerably longer in one direction than in the other direction, a U-piece secured within the inner end of said spout at its top and extending transversely parallel with the shorter diameter of said spout-end, a spool-shaped roller rotatably mounted on said U-piece 25 30 35 and having separated bearing surfaces forming

a spout-support engaging the upper surface of said gooseneck at points normally equidistant from the plane passing through the center of the gooseneck, said spout-support having such relation to the elongated cross-section of the inner 5 end of the spout and of the circular cross-section of the gooseneck as will cause gravity to maintain the spout in proper vertical relation to the gooseneck nozzle as the spout is moved along the same.

10 7. A water column comprising a standpipe and gooseneck nozzle supported on the upper part thereof of circular cross-section, a spout having an enlarged intermediate portion and a contracted inner end surrounding said gooseneck and of a cross-section considerably longer in one direction than in the other direction, and a spool-shaped roller secured within the inner end of said spout at its top and extending transversely parallel with the shorter diameter of said spout-end, said spool having separated bearing surfaces 20 forming a spout support engaging the upper surface of said gooseneck at points normally equidistant from a vertical plane passing through the center of the gooseneck, said spout support having such relation to the elongated cross-section of the inner end of the spout and the circular cross-section of the gooseneck as will cause gravity to maintain the spout in proper vertical relation to the gooseneck nozzle as the spout is 25 30 35 moved along the same, and a pair of chains, each embodying a pair of U-links and a compression spring having operative connection with the said U-links, for limiting the movement of the spout along its gooseneck support.

JOHN T. McGARRY.
